UNITED STATES PATENT OFFICE.

LOUIS JEAN LE CLAIR, OF MOORFIELDS, LONDON, ENGLAND, ASSIGNOR OF ONE-HALF
TO G. D. PETERS & CO. LIMITED, OF MOORFIELDS, ENGLAND, A LIMITED COMPANY.

WEATHER-STRIP OR DRAFT-EXCLUDER FOR WINDOWS, DOORS, AND THE LIKE.

1,124,148.

Specification of Letters Patent.

Patented Jan. 5, 1915.

Application filed October 23, 1913. Serial No. 796,861.

To all whom it may concern:

Be it known that I, LOUIS JEAN LE CLAIR, a subject of the King of Great Britain, residing at Moorgate Works, Moorfields, London, England, have invented new and useful Improvements in Weather-Strips or Draft-Excluders for Windows, Doors, and the like, of which the following is a specification.

10 This invention relates to weather strips or draft excluders especially applicable to sliding frameless windows for railway carriages and other vehicles, but also applicable to the doors of railway vehicles or to 15 other doors or windows or the like.

The sliding windows of railway and other carriages are frequently arranged in guides which are of considerably greater width at the lower parts than the sliding window 20 so as to allow the lower edge of the window, when being closed, to be moved over a fence plate, for the purpose of excluding wind and rain; in another class of window the guides are made of approximately the same 25 width as the thickness of the sliding sash or the window, cushions, pads or the like being arranged in the window frame, at the bottom of the sliding window, for preventing the entrance of wind and rain. In this latter class of window, which is the class to 30 which my invention is especially applicable, the pads or cushions are frequently made of felt or other material which after a certain amount of use fails to form a tight 35 joint and which, furthermore, is more or less injuriously affected by climatic conditions, and also, in some countries, by insects, and one of the main objects of this invention is to provide, in conjunction with 40 a window of the kind in question, improved means for excluding wind and rain.

According to my invention I provide what may be termed a laminated bar which is preferably made of a series of thin plates 45 of metal, vulcanite or other material, of a substantially imperishable nature, laid together to form a brushing edge and adapted to bend slightly in the direction of its width to form a tight joint against a window or 50 door when in contact with it.

To enable my invention to be fully understood I will describe the same by reference to the accompanying drawing, in which:—

Figure 1 is a sectional elevation through 55 the lower part of a sliding window and

framing having my improvements in connection with it. Fig. 2 is a view similar to Fig. 1, but showing the sliding window in a different position. Fig. 3 is a section on the line 3—3, Fig. 1. Fig. 4 is a view drawn to an enlarged scale of the draft excluder arranged in accordance with my present invention, and Fig. 5 is a view similar to Fig. 4, but illustrating a slight variation, and Fig. 6 is a sectional view illustrating the application of my invention to a door.

a indicates the framing around the window opening of a carriage and *b* the frameless window, sliding in grooves *c*, *c* formed in the framing *a* at the sides of the window opening, the said window at its lower part being fixed to a grooved bar *d* of metal, which in the drawing is represented as being carried at the upper end of a system of levers of the kind referred to in the specification of former Letters Patent granted to me No. 6181 of 1911, but which may be adapted to be supported by any other suitable means.

e, *e* are strips of felt or other packing material arranged in the grooves in which the window slides and *f*, *f* are wooden strips against which springs *g*, *g* bear with sufficient pressure to hold the glass *b* in contact with the strips *e* but not sufficient to prevent the window from being readily moved.

h is the weather strip or draft excluder constructed according to my invention, the said strip being composed of a series of thin plates *i*, *i*, *i*, advantageously made of copper or other relatively soft metal laid one upon another and secured together. In practice the several plates *i*, *i* are advantageously secured in a holder *j* provided with a cover plate *k* of metal, such as sheet brass having a certain amount of elasticity, so that it will be capable of returning to its normal position after displacement. This laminated bar *h* is arranged with its "brushing" edge extending slightly beyond the plane through which the lower part of the window moves and at an angle of say 45°, as shown in Fig. 2, so that when the window is moved to its closed position, as shown in Fig. 1, the plain face of the bar *d*, (or the lower part of the sash, if the window is mounted in a sash) by coming into contact with the "brushing" edge of the said laminated bar, will bend the latter

slightly as indicated in Fig. 1 and thus produce the necessary contact between the window and the said laminated bar to form a weather proof joint. The "brushing" edge of the laminated bar *h* is beveled so that the edges of all the plates *i*, *i* will lie in contact with the bar *d*.

l is a strip of felt or other material that is placed on the window framing immediately opposite to the laminated bar *h*, so that the window will be supported to enable it to bend the said laminated bar to the required extent to form a tight joint.

In some cases my improved laminated bar may be fixed on the inside of a window only to form a draft excluder.

Fig. 5 shows the laminated bar provided with a rigid cover plate *m* which extends nearly to the edge of the said bar above the spring cover plate *k*.

Although I have described my invention as applied to a sliding window it is obvious that it can be used in connection with a hinged door. In Fig. 6 which illustrates such an arrangement, *n* indicates the door frame and *o* the door, the laminated device *h* being shown as arranged in a recess cut in the door frame and the "brushing edge" arranged to project slightly beyond the surface of the said frame so that the edge of the door will close against it.

It will be obvious that in certain cases the arrangement hereinbefore described may be reversed, that is to say, the laminated bar instead of being fixed to a rigid part can be applied to the movable part and

adapted to coöperate with a plain surface on the rigid part.

Claims.

1. A weather strip or draft excluder composed of a series of thin metal laminæ or plates fixed together and designed to be applied in connection with a window, door or the like, in such a manner, that the closing of the said window, door or the like will cause the said weather strip or draft excluder to coöperate with a plain surface, against which a joint is to be made and slightly bend the said strip, substantially as described.

2. A weather strip or draft excluder wherein a series of thin metal plates capable of bending slightly are laid one against another and secured in a holder, substantially as described.

3. In a weather strip or draft excluder, the combination with a series of thin metal plates, of a plate of spring metal and a holder in which the said thin plates and spring plate are fixed.

4. In a laminated weather strip or draft excluder, the combination with a series of thin soft metal flexible strips, of a cover plate of spring metal, a holder in which the said plates are fixed and a projecting part above the level of said plates adapted to cover or shield the same.

LOUIS JEAN LE CLAIR.
